UNITED STATES PATENT OFFICE.

GEORGE MORE, OF RICHMOND HILL, AND EDWARD W. SPIES, OF NEW YORK, N. Y.

SPRAYING DEVICE FOR LIQUID PAINT AND THE LIKE.

1,169,558.

Specification of Letters Patent. Patented Jan. 25, 1916.

Application filed May 4, 1915. Serial No. 25,680.

To all whom it may concern:

Be it known that we, GEORGE MORE and EDWARD W. SPIES, both citizens of the United States, and residents, respectively, 5 of Richmond Hill, in the county of Queens and of the borough of Bronx, in the county of New York, State of New York, have invented certain new and useful Improvements in Spraying Devices for Liquid Paint 10 and the like, of which the following is a specification.

This invention relates to spraying devices for paint or the like, and it comprises, in a liquid paint receptacle having atomizing 15 means, certain novel features of improvement whereby devices of this character are rendered more convenient and efficacious in use.

Our invention in brief consists of a paint 20 receptacle having a handle by which it may be carried in practice; also having a paint delivery nozzle, and an air nozzle, in communication with a source of pressure supply, one of said nozzles being adjustable relatively to the other, whereby the degree of 25 suction force exercised by the air jet across the paint delivery nozzle may be varied to thus regulate the quantity of paint drawn outwardly and atomized. By this means a 30 lighter or heavier coat of paint may be applied to the surface under treatment, to suit the requirements.

The handle by which the receptacle is carried and operated in practice, is arranged 35 relatively to the position of the air jet nozzle in such manner that when said handle is grasped by one hand of the operator, the atomized paint is then directed forwardly of the operator toward the work, and we 40 provide a controlling valve in the line of the compressed air supply, for convenient operation by the same hand of the operator with which the receptacle handle is grasped, whereby the receptacle may be carried, the 45 paint spray therefrom directed, and the atomizing air controlled, all by manipulation of a single hand.

The air pressure nozzle is pivoted in manner to rock through a vertical arc, 50 whereby its attack across the orifice of the vertical paint delivery nozzle may be varied, adjustment being effected by a thumb screw, acting upon said air pressure nozzle, to regulate its degree of rocking movement, 55 and thus to direct its angle of attack, said thumb screw being conveniently disposed

for manipulation by the other or free hand of the operator.

Other features and advantages will hereinafter appear.

In the drawing: Figure 1 is a side elevation of an apparatus embodying our improvements. Fig. 2 is a vertical sectional view thereof, and Fig. 3 is a top plan view.

In carrying out our invention we employ 65 a receptacle for liquid paint, as 1, which may be in cylindrical form and of suitable size to contain a quantity of paint or the like, the combined weight of the receptacle and its contents being such as to be capable 70 of convenient handling by the operator with one hand. The receptacle is provided with a removable top or cover, which may be in the form of a screw cap, as 2, which latter may also serve as a mount for the spraying 75 or atomizing devices, whereby the liquid paint contents of the receptacle are applied to a surface to be coated.

A tube 3 extends downwardly from cap 2 within the receptacle, for the passage of 80 fluid paint, said tube penetrating the cap, and terminating above said cap in a delivery nozzle 4. An air delivery nozzle 5 is also mounted upon cap 2, having trunnions 6 by which it is pivoted in bearings 7, said nozzle 85 lying in a substantially horizontal position, with its exit orifice directed across the vertical axis of the nozzle 4, and said nozzle 5 being thus capable of swinging vertically, to vary the angle at which the air jet attacks the paint delivery nozzle, to thereby 90 regulate the extent of the suction force set up in inducing the exudation of paint from said nozzle 4 for atomization.

The nozzle 5 has a laterally enlarged portion or offset, as 8, through which is provided a vertical, threaded orifice, to receive a thumb screw 9, whose free end is adapted to bear against the upper surface of cap 2, and thus, by turning said thumb screw up 100 or down, to regulate the angularity of nozzle 5 relatively to nozzle 4. The nozzle 5, at a point anterior to its pivotal bearings, is tensionally connected to the upper surface of cap 2, as by a spring 10, whereby 105 the regulating action of the thumb screw is rendered effective.

A handle, as 11, by which the receptacle is held for service by one hand of the operator, is secured toward the rear portion of the receptacle wall, at one side of the medial line occupied by the horizontally 110

disposed nozzle 5, that position for the handle enabling it to be held most conveniently for the practice of the apparatus with the air nozzle directed toward the work. In the 5 illustration, the handle is shown as adapted for use by a right handed person, and its relative position may obviously be reversed for use by a left handed person.

The nozzle 5 is supplied with air under 10 pressure as by a flexible tube 12, which communicates with a valve, as 13, as by a branch tube 14, said valve also communicating, as by a branch tube 15, and a flexible tube 16 connected therewith, with a source of air 15 pressure supply, as 16^a. I have shown the valve casing as cylindrical, with a plunger 17 having a head 18 which is held to its seat 19 by a spring 20 placed around the exposed portion of the plunger, between the cylinder head and a push piece 21, thus holding the valve normally closed to prevent the passage of air. Said valve casing is attached to the receptacle 1, at its rear, a little to the left (in the example illustrated) of 25 the handle 11, where it is in convenient position to be operated by the thumb of that hand of the operator grasping the handle, this being as stated for use by a right handed person. Obviously the position of the 30 valve, relatively to the handle, would be reversed when intended for use by a left handed person.

It will be apparent, from the foregoing description, that the operator holding the 35 device by its handle 11, with one hand, in position to direct the induced, atomized paint toward the surface to be coated with paint, may with the free thumb of the same hand depress the valve plunger for the supply of compressed air, and may at will shut off the supply by release of the thumb pressure, thereby allowing the valve spring to close the valve. Also, at the time of spraying atomized paint in the manner indicated, 40 the operator may, with his other hand, manipulate the thumb screw 9 to thereby rock the nozzle 5, for the purpose of regulating its angle and consequently the degree of suction applied to the paint nozzle 4. To 45 provide a quick means of connecting and disconnecting the flexible tube 12 with nozzle 5, as is necessary in removing and reapplying the cap 2, we may provide a threaded slip coupling, as 22, or equivalent 50 device.

Variations may be resorted to within the scope and spirit of our said invention, and parts thereof used without others.

We claim:

60 1. A device for spraying liquid paint and the like, the same comprising a receptacle, a stationary vertical paint delivery nozzle communicating with the interior of said re-

ceptacle, an air nozzle horizontally disposed and directed toward the vertical axis of said paint delivery nozzle, a pivotal support for said air nozzle enabling it to swing vertically, relatively to said paint delivery nozzle to vary the degree of suction force exerted upon said paint delivery nozzle, and 65 means for adjusting said air nozzle in its vertical swinging movement.

2. A device for spraying liquid paint and the like, the same comprising a receptacle, 70 a paint delivery nozzle communicating with the interior of said receptacle, an air nozzle in communication with a source of air pressure supply, the axes of said nozzles being in intersecting relation, and means for swinging one of said nozzles relatively to 75 the other, to vary the degree of suction force exerted by pressure from said air nozzle upon said paint delivery nozzle.

3. In a device for spraying liquid paint and the like, having a receptacle, the combination of a paint delivery nozzle communicating with the interior of said receptacle, 80 an air nozzle pivotally supported upon said receptacle, and in communication with a source of air pressure supply, a spring normally holding said air nozzle in a set position relatively to said paint delivery nozzle, a threaded portion upon said air nozzle, and a thumb screw engaged in said threaded portion and bearing upon said receptacle, for the purpose of regulating the 85 position of said air nozzle relatively to said paint delivery nozzle, to vary the degree of suction force exerted in atomizing.

4. In a device for spraying liquid paint and the like, having a receptacle, and a removable cover therefor, the combination of 100 a fixed paint delivery nozzle on said cover, communicating with the interior of the receptacle, a pivotal air nozzle also mounted on said cover and movable with relation to said paint delivery nozzle, to vary the suction force directed thereon, means controlled by one hand of the operator to actuate said air nozzle, an air controlling valve, and a handle, both mounted on the rear portion of the receptacle, near each other, whereby 105 said valve may be operated by the operator's other hand which grasps the handle in holding and manipulating the device, means 110 communicating compressed air to said valve, and a tube connecting said valve and air nozzle.

Signed at 45 Classon ave. Brooklyn in the county of Kings and State of New York 120 this 30th day of April A. D. 1915.

GEORGE MORE,
EDWARD W. SPIES.
